UNITED STATES PATENT OFFICE.

SEVERIN HALVORSEN, OF SEATTLE, WASHINGTON, ASSIGNOR TO NEWSPAPER STUFFING MACHINES CO., OF SEATTLE, WASHINGTON, A CORPORATION OF WASHINGTON.

NEWSPAPER-STACKING MECHANISM.

Application filed August 28, 1920. Serial No. 406,579.

To all whom it may concern:

Be it known that I, SEVERIN HALVORSEN, a citizen of the United States of America, and resident of the city of Seattle, in the 5 county of King and State of Washington, have invented certain new and useful Improvements in Newspaper-Stacking Mechanisms, of which the following is a specification.

10 My invention relates to mechanisms for delivering and stacking newspapers. It has been designed chiefly for use in connection with a newspaper stuffing machine, but it is evident that it might be employed for other 15 analogous uses.

The device is intended to receive a series of papers as they are delivered successively, as from a newspaper stuffing machine, or from any analogous source, and to stack the 20 same in an orderly relation, so that they may be removed in bodies containing a considerable number of papers at the same time.

25 The object of my invention is to provide a machine for doing this work which will perform the work in a more perfect manner than the devices previously used for like purpose, and one which is particularly adapted for handling the papers as delivered 30 from a newspaper stuffing machine.

One of the objects of my invention is also to provide a device of this sort which will receive the papers from a carrier or conveyor, one at a time, and which will add 35 these papers as received, to the bottom of a stack of papers, whereby the stack of papers is gradually built up from the bottom and with the papers lying in horizontal planes. Other objects of my invention will be dis- 40 closed by an inspection of the drawings and a study of the description thereof contained in this specification.

45 My invention consists of the parts and combinations of parts which are herein illus- trated and described, and which are partic- 50 ularly pointed out in the claims which terminate this specification.

55 The accompanying drawings show the manner of employing my invention in a structure which is that now preferred by me.

50 Figure 1 is a top or plan view of the delivering and stacking mechanism.

55 Figure 2 is an end elevation, or view taken

in line with the conveyor which delivers the 55 papers to the stacking machine.

Figure 3 is an elevation showing the back side of the device.

Figure 4 is a sectional elevation taken upon the plane indicated by the line 4—4 of 60 Figure 1.

Figure 5 is a detail view showing a part of the mechanism, the same being taken upon a plane 5—5 of Figure 1.

The particular type of mechanism with 65 which the device, as herein shown, has been designed to operate, is the newspaper stuffing machine of the type of construction shown in my application, Serial No. 290,184, and the improved form thereof shown in 70 another application 406,578, which is filed coincidently herewith. It is, however, usable with other types of apparatus.

In this type of machine, different sections 75 of the paper are combined to form the stuffed paper while being conveyed through an assembling chute or trough in a horizontal direction. In the latest form of this device, as shown in my said application 406,578 which is filed coincidently herewith, 80 the general plane of this assembling chute and of the papers, as they are being passed thereto, is approximately horizontal. To obtain certain advantages the general plane of 85 this chute and of the papers has been tilted, so as to make a comparatively small angle with the horizontal, but it approaches the horizontal plane much more nearly than it does a vertical plane. The angle of the bottom surface of this chute is shown by the 90 dotted lines at A in Figure 2, which indicate the bottom plate of this chute.

The means employed in the machine above referred to for conveying the assembled 95 papers lengthwise of the chute, includes an endless belt or chain 1, which passes about wheels 10 at each end of the chute, whereby the same is driven in a steady continuous manner. As a means for engaging the papers to insure that they be carried along 100 and positioned relative to the other parts in proper position for receiving the various sections, I employ a set of fingers, as 11, which project from the chain and through a slot in the floor of the chute a sufficient 105 distance to engage the following or rear edge of the papers to insure that they be carried along.

In employing this form of conveying means there is a tendency for the propelling fingers 11, as they pass about the wheel 10 at the delivery end of the conveyor, to press down upon the papers and thus cause trouble, either by tearing or deforming the papers. One of the objects of my invention is to provide means whereby the papers, as they reach the delivery end of the conveyor 5 and just before being discharged therefrom, are given an accelerated feed movement, sufficient to cause them to leave behind the fingers 11, which have heretofore propelled them, and get out of the way of the feed 10 fingers before they start turning about the 15 wheels 10. The manner of securing this result is best shown in Figures 1, 4, and 5.

At a level to come below the bottom plates 12 of the assembling trough, are placed feed 20 tapes or belts 21, which are mounted upon wheels or rollers 20 so that they may turn freely. These form supports for the papers during the transfer thereof from the conveyor of the stuffing machine to the paper 25 stacking device. Journaled above the assembling chute of the stuffing machine and extending across the same, are two shafts 21' and 22. The shaft 21' is a fixed shaft which functions mainly as a support for other parts. 30 The shaft 22 rotates and has thereon pulleys 23, over which pass accelerating belts 24. These belts also pass over rollers 25, which are supported above the belts 21 which are beneath the papers. These pulleys 35 or rollers 25 are journaled upon the outer or swinging end of arms 26, which are pivotally mounted concentric with the shaft 22.

These levers are, however, not carried upon the shaft 22 but upon flanged bosses 27' carried by the lower end of the arms 27, which arms are secured to and supported from the non-rotative bar or shaft 21'. The arms 26 are yieldingly forced downward by the action of torsion springs 28, one end of which 45 is secured to the arms 27 and the other to the arms 26. The downward movement of the arms 26 is limited by means of stops carried respectively by the arms 26 and 27. Such stops are more clearly shown in Figure 5, consisting of an arm 29 carried by the arm 27 and extending therefrom, and a bolt 29^a carried by the arm 26. By this manner of construction the weight of the arms 26 does not act in any way to produce 50 friction to retard the turning of the shaft 22.

The means by which the shaft 22 is turned and the belts 24 are driven, is so proportioned that the speed of movement of the belt 24, and also of the belt 21, is materially 55 greater than the speed of movement of the conveyor chain 1. The point where the two belts 24 and 21 come close together, being the point where they engage the papers, is located just beyond the end of the conveyor 60 chain 1. It is, however, so placed that these

belts will engage the papers so as to accelerate their movement before the paper moving finger 11, carried by the conveyor chain, starts to make the turn about the wheel 10. In consequence, the belt will be 70 accelerated and driven ahead of the fingers 11, so that when said fingers start to sweep about the wheel 10, the paper will have been moved out of engagement therewith.

The paper, as discharged from the conveyor chain, is received upon a plate 3. This plate is shown as more nearly approaching a horizontal position than the lower side of the assembling chute. This is a matter which is, however, not strictly essential, although, I prefer to so arrange matters. The plate 3 is supported in such a way as to move freely up and down. The supporting means illustrated consists of a plunger 30, which is mounted to vertically reciprocate within a stop guide, as 31. At one side it is shown as having a pin 32 projecting and engaged by a link 33, which link is connected with an arm 34 secured to, or mounted upon, a shaft 35. The manner of operating this herein shown, consists of securing to the arm 34, or to the shaft 35 thereof, a short arm 36, which is connected with a rod, as 37, reciprocated by any suitable mechanism. The manner of reciprocation of the plate 3, consists of a quick uplift, followed almost immediately by a drop to its normal position. The plate 3 will remain long enough in its lowered position, or that shown by full lines in Figure 2, to receive the next paper discharged from the assembling chute.

The plate 3 is enclosed by guide and retaining fingers or posts, as 4, which enclose the papers as they are stacked up sufficiently 105 to maintain them in position. Associated with the vertically reciprocating plate 3 are holding fingers which sustain the stack of papers as assembled. These fingers project inward from the post 4 and are movable outwardly to permit passage of the papers as they are added to the pile at the bottom, and are then quickly moved inward so as to put them underneath the stack of papers, thus retaining each paper in position as it 110 is placed beneath the stack. To permit the holding or sustaining finger being in this inner position while the plate is dropping, the plate is provided with notches, as 38, in its edges, located to conform with the 115 position of the paper holding fingers.

I have shown two types of paper holding fingers. One type consists of arms or bars 40, which are pivoted at their lower ends, as at 41, and have an off-set finger, as 42, 120 at their upper ends. These fingers 42 normally project inward beyond the inner faces of the retaining bars 4, enough to supply ample support for this edge of the stack of papers. The arms 40 are normally drawn 125

inward by the action of the spring 42'. The lower surfaces of the supporting fingers 42 are preferably on an incline, as is clearly shown in Figure 2, so that as the edge of the 5 paper is being raised by the plate 3, engagement of the paper therewith, will force the arm 40 outward until the paper passes the point of the terminal finger 42.

The other type of supporting fingers are 10 shown at 43. These are mounted to reciprocate in suitable guides. Their reciprocation is secured by means of lever arms 44, which are pivotally secured to a shaft 45, which shaft is oscillated in any suitable manner, 15 as through the means of arms 46 secured thereto, moved through links or rods 47, which are in turn reciprocated by a cam 48 carried by a shaft 49. This mechanism is so timed that the supporting fingers 43 are withdrawn just before the plate 3 reaches their level and are returned to project under the paper before the plate starts to fall.

To prevent the papers, as delivered from the accelerating belts to the plate 3, from rebounding, I provide stops, consisting of bars 5 mounted upon the arms 26, these being of an angular or L-shape and pivoted at 50 upon the arms 26. This has an upwardly 20 extending arm 51, which extends upward alongside of that edge of the stack of papers. This arm has a slot 52 through which the shaft of the rollers 25 pass, thereby forming a stop to limit the downward drop of the 25 part 5. The paper will pass easily under this but it will immediately drop down behind the paper, so as to prevent rebounding of the paper.

In connection with the above paper stacking mechanisms, I have provided means 40 whereby counting of the papers is facilitated. As a stop for the papers when delivered upon the table 3, I provide a plate 45 6, carried by an arm or arms 60 pivoted to swing towards and from the paper receiving 50 tables 3, as upon the pivot 61. Alongside of this is a toothed or ratchet wheel 63 having secured thereto a disk 64 which has a recess 55 adapted to receive a pin or roller 62 carried by the arm 60. The ratchet wheel 63 is intermittently turned through a pawl 65 carried by arm 66 which is reciprocated through rod 67, the latter being actuated in conformity with the addition of the papers to the stack, through any suitable mechanism. When the disk 64 is in position to receive the roller 62, the plate 6 will be forced outward from the table 3 beyond its normal position, as is indicated in Figure 3, permitting one paper to extend farther in this direction than the others. These projecting papers will show in the stack and make counting out of a definite number easy. A spring, as 68, acts to push arm 60 outward.

65 To counteract the weight of the reciprocating

ing plate 3 I show a spring 7 which acts, through compression upon arm 70, upon shaft 35 by the oscillation of which the plate 3 is moved.

By this method of stacking the papers they 70 are placed in convenient position and at a level where no stooping is required. Also the space required for the stacker is less than when using a horizontal belt for the reception of the papers.

75 What I claim as my invention is:

1. In a newspaper handling machine, an 80 endless conveyor for the papers having projecting paper-engaging fingers, paper accelerating means comprising endless belts engaging the under side of the papers as they are being discharged from the main conveyor, and complementary belts and their operating means located above the papers and mounted to swing about one end and with the other end yieldingly bearing upon the paper.

2. A newspaper delivering mechanism 90 comprising an endless conveyor having projections engaging the paper edges, an accelerating means comprising a belt beneath the papers and extending beyond the delivery end of said conveyor, a complementary belt mounted above the papers, a frame upon which said upper belt is carried, said frame being hinged at one end and swinging to cause its other end to engage the papers in passing at a point over the lower belt and means for limiting the downward movement 95 of said upper belt.

3. In a newspaper stuffing machine, an 100 endless conveyer for the papers, and a paper accelerating feed device positioned to engage the papers just before leaving the main conveyor, and means whereby said accelerating feed device is automatically adjustable for different thicknesses of papers.

4. In a newspaper stuffing machine, an 110 endless conveyor for the papers, accelerating belts positioned to engage the papers from above and below just before leaving the main conveyor, the accelerating belts at one side of the paper being mounted to swing about one end to thereby adjust for papers of different thickness.

5. A paper stacking device comprising 120 paper supporting arms pivoted to swing beneath and to clear the edges of the paper, a vertically reciprocating paper carrier movable upward beyond the paper supporting surfaces of said arms, and cut away to clear said arms, said paper supporting arms being engaged by the papers to be thereby swung outward beyond the edges of the 125 papers.

6. A paper stacking mechanism comprising vertical stack-retaining bars, paper supporting members movable to extend under and to be withdrawn from beneath the 130

- 43
- papers, a paper carrier vertically reciprocating within said retaining bars and to travel from below to just above said paper supporting members, and means synchronized with said paper carrier to withdraw the paper supporting members as the carrier passes them on the upward movement and returns beneath the papers prior to the downward passage of the carrier.
- 10 7. In a newspaper stuffing machine, a carrier for the stuffed papers delivering them horizontally, a stacking mechanism receiving the papers from said carrier, and paper retaining arms hinged back over said carrier to swing vertically and having a vertically extending face on their outer end positioned to conform to the position of the rearward edge of the paper as it is received by the stacking mechanism.
- 15 8. The combination with a carrier for papers delivering them horizontally, and a stacking mechanism, receiving papers from said carrier, of bars pivoted over the carrier and swinging vertically with their swinging ends engaging the papers as they pass, said bars having their swinging ends positioned to conform in location to the adjacent edge of the stack being formed.
- 20 9. The combination with a paper carrier delivering papers horizontally, of a stacker receiving papers from said carrier and adapted to build the stack from below, and retaining bars positioned to conform to that edge of the stack which is towards the carrier and yieldingly supported to engage and be raised by the papers as delivered by the said carrier.
- 25 10. The combination with a paper carrier delivering papers horizontally, of a stacker receiving papers from said carrier and adapted to build the stack from below, and retaining bars pivoted over the carrier and having their free ends vertically movable and provided with a vertical finger positioned to conform to that edge of the stack which is towards the carrier, said bars being engaged and raised by the papers as delivered by the carrier.
- 30 11. In a newspaper stacking machine, a carrier horizontally delivering the papers, an accelerating feed device for said papers acting to accelerate their movement as delivered from the said carrier and having a swinging frame carrying a feeding element engaging the upper surface of the papers in passing, and a paper retaining bar supported by said frame to yield vertically and having a vertical face conforming to that edge of the stack which is towards the carrier.
- 35 12. In a newspaper stacking machine, a carrier horizontally delivering the papers, an accelerating feed device for said papers acting to accelerate their movement as delivered from the said carrier and having a
- swinging frame carrying a feeding element engaging the upper surface of the papers in passing, and an L-shaped retaining bar pivoted at one end for vertical movement upon said frame with its other arm extending upwardly and positioned to conform to that edge of the stack which is towards the carrier, said bar being engaged and raised by the papers as discharged from the carrier. 70
13. In a newspaper stacking machine, a carrier horizontally delivering the papers, an accelerating feed device for said papers acting to accelerate their movement as delivered from the said carrier and having a swinging frame carrying a feeding element engaging the upper surface of the papers in passing, and an L-shaped retaining bar pivoted at one end for vertical movement upon said frame with its other arm extending upwardly and positioned to conform to that edge of the stack which is towards the carrier, said bar being engaged and raised by the papers as discharged from the carrier, and means limiting the swing of said retaining bars relative to the said frame. 75
14. The combination with a paper carrier delivering papers horizontally, of a stacker receiving papers from said carrier and adapted to build the stack from below, means for accelerating the papers delivered by the carrier on to the stacker, a stop for the papers, and means adapted to be disposed behind the papers on the stack to prevent rebound of the papers striking said stop. 80
15. The combination with a paper carrier delivering papers horizontally, of a stacker receiving papers from said carrier and adapted to build the stack from below, means for accelerating the papers delivered by the carrier on to the stacker, a stop for the papers, means adapted to be disposed behind the papers as delivered to the stack for preventing their rebound when striking said stop, and means for actuating said stop to permit certain of the papers delivered to the stack to project therefrom a limited distance. 85
16. The combination with a paper carrier delivering papers horizontally, of a stacker receiving papers from said carrier and adapted to build the stack from below, means between the carrier and stacker for accelerating each paper as the same is delivered from the former, a movable stop on the stacker, means carried by said accelerating means for preventing rebound of the papers when striking said stop, and means for automatically withdrawing said stop at predetermined intervals to permit certain of the papers to project beyond the stack. 90
- Signed at Seattle, King County, Washington, this 23rd day of July, 1920.
